DANIEL APPEL, OF EAST CLEVELAND, OHIO, ASSIGNOR TO UNION PAPER BAG MACHINE COMPANY, OF PHILADELPHIA, PENNSYLVANIA, A CORPORATION OF PENNSYLVANIA.

PAPER BAG.

1,029,783.

Specification of Letters Patent. Patented June 18, 1912.

Application filed October 26, 1911. Serial No. 656,824.

To all whom it may concern:

Be it known that I, DANIEL APPEL, a citizen of the United States, residing at East Cleveland, in the county of Cuyahoga and State of Ohio, have invented new and useful Improvements in Paper Bags, of which the following is a specification.

My invention relates to that class of paper bags which may be called "bellows sided satchel bottom bags", such in general character as the bag shown and described in reissued Letters Patent #10,083 dated April 11, 1881; and my object is to so construct such bags that the bottom may be readily folded without undue strain; that they may have a smoothly pasted bottom inside of the bag, and that they may have a bottom which is strengthened and more safely sealed by doubling over portions of the bottom, and by making the proportion of the last folded portions of the bottom in such a manner that they will overlap the first folded portions of the bottom.

The method of making this paper bag consists in making a bellows-sided blank provided with two slits in the bellows fold at the end of the blank, which is to form the bottom. Then a portion of the blank is opened up to form the bottom, resulting in the developing of the wellknown inside triangular folds, thereby spreading outwardly the two bellows side-folds, form side flaps, and folding down the two end-folds, or flaps, interlapping one below the other, paste being applied between these interlapping folds; then the two side-flaps are provided with paste, and folded over upon the previously folded end-flaps, thus completing the bottom. The mouth end of the tube may be provided with any of the wellknown thumb notches or lips, if desired.

In the drawings, Figure 1 is a perspective view of the bag blank in rectangular form, and provided with four slits in the bottom end. Figs. 2, 3 and 4 are plan, side and end views, respectively of the blank of Fig. 1, showing the blank collapsed into a bellows-sided tube form. Figs. 5, 6 and 7 show plan, side and end views respectively, of the bellows sided blank with the bottom partially folded, in which the two side-flaps are spread outwardly and the two end-flaps are partially folded together. Fig. 8 is a plan view of the blank with the bottom flattened down, the two side-flaps projecting

outwardly. Fig. 9 is a plan view of the completed bottom, wherein the side-flaps are folded over the end-flaps. Fig. 10 shows a perspective view of the bottom of the completed bag, showing the bag opened up. Fig. 11 is a perspective view of the inner portion of the bottom of the bag, the tube portion of the bag being broken away. Fig. 12 shows a modified form of slitted blank.

In the figures:— 12 represents the blank. 13 and 14 represent the bellows folds.

15—15 show two slits cut in the bottom end and at each side of the blank, extending from the bottom end of the blank inwardly a short distance.

16 represents the first end-flap and 17 the second end flap.

18 and 19 are the tabs of the two side-flaps.

20 shows a crease formed across the bellows tube, and 21 shows another crease which is preferably made in the blank and in advance of the crease 20, equal to the depth of the bellows folds 13—14.

23 and 24 show the partly developed inside triangular folds.

25 shows a line of paste on the end-flap 16, and 26 and 27 show lines of paste in Fig. 8, printed on the folded down end-flaps, for pasting the side-flaps.

The making of the four slits in the blank is preferably done while the paper is drawn over the wellknown tube forming apparatus, and while it is in rectangular form, as shown in Fig. 1; these slits are made in the bellows sides of the blank, between the longitudinal fold lines thereof. They are disposed in generally longitudinal relation to the bag blank. They may, however, be curved, or may be inclined as shown by the slits 30 in Fig. 12. These slits divide each of the bellows sides into three portions. The middle portions on each side form the single ply tabs 18 and 19 of the side flaps; while the marginal portions, separated from these tabs by the slits 15 remain integrally joined to the upper and lower plies of the bag blank, and thus become side wings of the end flaps 16 and 17, when folded down to the position shown in Fig. 8, extending across the hinge lines 28 and 29 of the side flaps. They thus serve to reinforce the hinge and base portions of the side flaps, and being doubled over with those flaps in completing the bag bottom, they form

safety sealing flaps to securely seal the side edges and corners of the bag bottom against leakage.

The end flaps 16 and 17 are made long enough to interlap each other when folded down, as shown in Figs. 8 and 9; and these flaps are preferably pasted together by a line of paste 15, applied to the interlapping portion of one of the flaps. These interlapping portions form a reinforcing band which extends entirely across the bottom of the bag in its longest direction; and also extends across and reinforces the hinge lines 28 and 29 and the base of the side flaps. The tabs 18 and 19 are preferably proportioned so that when folded down upon the end flaps, as shown in Fig. 9, they are wider than the reinforcing band formed by the interlapping ends of the end flaps. Lines 26 and 27 extend across the said band, and also extend on opposite sides of that band to the sides of the bag bottom, as shown in Fig. 8, thus uniting the side flaps to the end flaps in such a way as to reinforce the bottom of the bag to best advantage, over a large proportion of its surface. This interlapping and reinforcing arrangement of the flaps produces a strong, flat, tight and smooth bottom without making the side flaps long enough to meet or interlap at the center of the bag, thus enabling a correspondingly shorter blank to be employed, and thereby economizing in material without sacrifice of strength or utility.

Having now described my invention, what I claim as new, and desire to secure by Letters Patent is:—

1. As a new article of manufacture, a paper bag of the class specified, having its bottom forming side flaps folded upon the

outside of its end flaps, the said side flaps having a plurality of plies crossing their respective hinge portions, forming safety sealing flaps, and terminating in single ply portions pasted flatly upon the end plies. 45

2. As a new article of manufacture, a paper bag of the class specified, having end flaps folded and interlapping to form the inner portion of the bottom, the outer portion of the bottom being formed by side 50 flaps each having a plurality of plies across its hinge portion, terminating in single ply tabs of a width greater than the interlapping portion of the end flaps.

3. As a new article of manufacture, a paper bag of the class specified having its bottom formed of end flaps and side flaps, the end flaps overlapping each other across the bottom of the bag and extending beyond the hinge lines of the side flaps, the said 60 side flaps terminating in single ply tabs pasted upon the outside of the end flaps.

4. As a new article of manufacture, a paper bag of the class specified having its bottom formed of end flaps overlapping 65 each other and pasted together across substantially the entire width of the bag, the said end flaps extending into and forming reinforcing plies for the side flaps, and the said side flaps terminating in single ply 70 tabs pasted flatly upon the outside of the end flaps.

In witness whereof I have signed my name to this specification, in the presence of two subscribing witnesses.

DANIEL APPEL.
